APPARATUS FOR COATING ARTICLES BY
IMMERSION

Herbert L. Davis, Walpole, Mass., assignor to The B. F. Goodrich Company, New York, N. Y., a corporation of New York

Application September 19, 1950, Serial No. 185,650

8 Claims. (Cl. 118—56)

This invention relates to an apparatus for coating articles, and pertains more particularly to a method and apparatus for applying a coating or deposit of a liquid coating composition on a base member.

An object of this invention is to provide an apparatus for depositing a liquid coating composition on base members or forms of a desired configuration.

Another object of this invention is to provide continuous conveyor apparatus for depositing a coating or deposit of rubber-like material on forms of a desired configuration which forms are readily detachable from the conveyor system and can readily be replaced with other forms.

Another object is to provide an apparatus for continuous manufacture of hollow rubber articles such as boots and shoes.

A further object is to provide an apparatus for continuous coating of base members which vary in size or shape.

A further object is to provide an apparatus for immersing forms successively in a plurality of liquid baths while the forms are advancing along a desired path.

It is also an object to provide means for dipping forms to varying depths in liquid baths while continuously advancing the forms around a close path.

Another object is to provide means for varying the perpendicularity of dipping forms while continuously advancing them through a succession of dipping stations.

Another object is to provide an apparatus for raising and lowering a form and independently varying its angular position while advancing it in a plane through a plurality of successive dipping stations.

Other objects of this invention will be apparent from the drawings and description which follow.

Apparatus heretofore devised for coating articles has not been entirely satisfactory, in that the apparatus is limited to a particular size or shaped article which it can accommodate. Also conventional conveyor coating apparatus is not capable of lowering a base member to numerous desired depths permitting the form to be completely or partially coated as the desired situation might require. Furthermore, the angle at which a dipping form enters or is withdrawn from a liquid dipping bath is not capable of being readily altered by convenient economical means in conventional conveyor coating apparatus.

I have invented apparatus which eliminates the limitations and disadvantages enumerated above inherent in conventional conveyor coating apparatus. Apparatus within the purview of my invention advances a base member over coating stations and is provided with adjustable mechanisms which permit the base member to be lowered into and withdrawn from a dipping bath at numerous desired angles and also permit the base member to be lowered into a dipping bath to numerous depths.

To more fully illustrate apparatus within the purview of this invention, one embodiment of the invention is shown and described, however, it will be understood that I do not limit my invention to this embodiment.

In the drawings:

Fig. 1 is a view in side elevation of selected portions of one embodiment of this invention;

Fig. 2 is a fragmentary side elevation view of the upper and lower cam tracks of the embodiment shown in Fig. 1;

Fig. 3 is a section on line 3—3 of Fig. 1;

2

Fig. 4 is a top plan view of the embodiment of this invention shown in Fig. 1;

Fig. 5 is a fragmentary side elevation view of the upper cam track showing the adjustment mechanism by which the cam surface of the upper cam track can be altered;

Fig. 6 is a section on line 6—6 of Fig. 5;

Fig. 7 is a section on line 7—7 of Fig. 5; and

Fig. 8 is a section on line 8—8 of Fig. 5.

Referring to the drawings, the apparatus comprises a main frame 10 which forms a support for various elements of the apparatus. A continuous chain conveyor 11 travelling around sprocket-wheel 12 which is driven by a multiple-speed motor 13 through gears 14, 14 and around idler sprocket-wheel 15 advances carriages 17, 17 secured to the links of chain 11 by means of a lug 18 and pin 19 over dipping tanks 20a, 20b, 20c, 20d, which contain the desired dipping baths.

Each carriage 17 comprises a frame 21 to which are secured rollers 22, 22 and rollers 23, 23 which bear against stationary pipe track 24 permitting carriages 17, 17 to be moved along the track as chain 11 advances around sprocket-wheel 12 and sprocket-wheel 15. Frame 21 of each carriage 17 is restrained against rotation about pipe track 24 by a roller 25 which is journaled on frame 21 and which bears against and travels in upper channel track 26, which is in turn secured to main frame 10.

Each carriage 17 contains a lever arm 28 which is rigidly secured to one end of a shaft 29 housed in frame 21 and a second lever arm 30 which is rigidly secured to the other end of shaft 29, so that lever 28, shaft 29 and lever 30 move as an integral unit. Rollers 31 and 32 are journaled on opposite ends of shaft 33 housed in the outer end of lever arm 30. In the outer end of lever arm 28 is housed rotatable shaft 34 having lever arm 35 secured at one end thereof and form supporting or clamping member 37 secured at the opposite end serving to hold one or more boot forms 38 to which the coating is to be applied.

Hollow shaft 39 is housed in frame 21 and is concentric with shaft 29, being free to rotate independently thereof. Rigidly mounted on one end of shaft 39 is double-ended lever arm 40, and secured to the other end of shaft 39 is lever arm 41 having roller 42 journaled on its outer end. One end of lever arm 40 is rigidly connected to the outer end of lever arm 35 by means of connecting rod 43, while the other end of lever arm 40 is secured to carriage frame 21 through compression spring 44.

Lever arm 41 is normally maintained in a raised position by reason of the thrust exerted upon lever arm 40 by compression spring 44, while lever arm 30 is normally maintained in a lowered position by reason of its own weight together with the weight of form 38 and lever arm 28 secured to the opposite end of shaft 29.

The position of lever arm 28 is controlled by cam tracks 45 and 46, the upper faces of which are alternately engaged by rollers 31 and 32.

Cam track 45 comprises several generally horizontal sections of angle iron rigidly secured to main frame 10 having downwardly sloping end portions 48, 48 forming an interrupted cam surface, as shown in Fig. 2. Disposed between the interrupted areas of cam track 45 are vertically movable cam track sections 46 on which roller 32 of lever arm 30 bears. Each movable cam track section 46 is pivotally mounted on supporting members 49, 49 which are secured at their midpoints to shafts 50, 50 housed in bearings 51 secured to main frame 10. The lower ends of supporting members 49, 49 are linked together by means of connecting bar 52.

Control arm 53 is keyed to one of the shafts 50 and carries a trunnion bearing 54 at its outer end which rides on threaded shaft 55. Handwheel 56 provides means for turning shaft 55 and raising or lowering control arm 53, which in turn rotates shaft 50 to which it is secured and raises or lowers cam track section 46 altering the lowermost position of lever arm 30.

The position of lever arm 41 is controlled by cam track 58 against the lower face of which roller 42 bears.

As shown in Fig. 5, cam track 58 comprises generally horizontal cam track sections 59, 59, which may be rigid-

ly secured to main frame 10 or comprise cam track sections which are capable of being moved vertically while being maintained generally horizontal by suitable adjustment means, generally horizontal extensible cam track sections 60 and inclined cam track sections 61, 61 connecting cam track sections 59, 59 and cam track sections 60 to form a continuous track. Each cam track section 59 is hollow and is provided with a slot 62 in its bottom face through which an inclined track member 61 passes. Roller 63 and shaft 64 are journaled in the upper end of track member 61, roller 63 rolling within hollow track 59 as shown in Fig. 8. Shaft 64 passes through slot 65 in the side of track 59 and has threaded shaft 66 secured to its outer end by means of setscrew 67. Tapped hollow shaft 68 is journaled in bearing 69 secured to main frame 10 and engages the end of threaded shaft 66. Handwheel 70 secured to the end of shaft 68 provides means for turning it and thus moving the upper end of track member 61 in track section 59. As shown in Fig. 7 roller 71 and shaft 72 are journaled in the lower end of track member 61, roller 71 rolling along guide 73.

Extensible track member 60 includes a housing consisting of sideboards 75, 75, spacer 76 and separator 77. Sliding rails 78, 79 are mounted in the housing on each side of separator 77 and keyed thereto. One end of rail 78 is pivotally secured to the lower end of one of inclined track members 61 by means of shaft 72, and the opposite end of rail 79 is similarly secured to the other inclined track member 61.

Track member 60 and guide 73 are pivotally mounted on brackets 81, 81 which are secured at their midpoints to shafts 82, 82 housed in bearings 83, 83 secured to main frame 10. The upper ends of brackets 81, 81 are linked together with connecting rod 84, one end of which is pivotally secured to threaded shaft 85 passing through a threaded bearing 86 pivoted on main frame 10. Handwheel 87 secured to threaded shaft 85 provides means for rotating the shaft. Rotation of handwheel 87 moves connecting rod 84 laterally which in turn rotates brackets 81, 81 about shafts 82, 82 and raises or lowers track section 60 and guide 73 together while keeping them horizontal.

The operation of the apparatus is as follows:

A form 38 which has been attached to a carriage 17 by means of clamping member 37 is advanced by chain conveyor 11 toward the first dipping tank 20a containing a solution of a form lubricant. Roller 31 of the carriage 17 bears on a horizontal portion of the cam surface of cam track 45 maintaining form 38 in a maximum raised position and roller 42 bears against the cam surface of a stationary cam track section 59, 59 maintaining lever 41 of the carriage 17 and consequently form 38 at its maximum rotation, so that form 38 will pass over the edge of tank 20a and be in a position for dipping.

After form 38 has passed over the edge of tank 20a, roller 31 rides down inclined portion 48 of cam track 45 permitting lever 30 and lever 28 to rotate downwardly lowering form 38 into the dipping solution contained in tank 20a. Simultaneously roller 42 is urged down inclined section 61 of cam track 58 rotating lever 41 and lever 40 downwardly. The movement of lever arm 40 is transmitted to lever arm 35 through linkage 43, causing clamping member 37 and boot form 38 to rotate about shaft 34 as an axis.

As roller 32 contacts cam track section 46 the rotation of lever 30 is terminated and roller 31 rides clear of cam track 45. If it is desired that form 38 be lowered further into the dipping bath, cam track section 46 is lowered by rotating shaft 55 in the appropriate direction, which adjustment increases the effective cam surface of the inclined cam surfaces 48, 48 of cam track 45. As roller 42 of carriage 17 bears against a horizontal extensible cam track section 60 the rotation of lever 41 and consequently of form 38 is terminated determining the angle at which form 38 will travel through the dipping bath; the angle being altered by raising or lowering cam track section 60 by rotating shaft 85.

Accordingly, the toe of form 38 enters the dipping solution first, as shown in the first position of Fig. 1, and only after the sole portion of the form is completely submerged is the form rotated to a vertical position as shown in the second position of Fig. 1. In this manner turbulence and splashing of the dipping solution upon entry of the form is minimized and entrapment of air bubbles under the shank portion of the form is avoided

while at the same time providing an even, horizontal upper edge on the dipped portion.

When carriage 17 has been advanced through the dipping bath a desired period of time, roller 31 is urged up inclined portion 48 of cam track 45 rotating lever 30 and consequently raising form 38, roller 32 being lifted clear of cam track section 46; simultaneously roller 42 is urged up inclined cam section 61 of cam track 58 by compression spring 44 permitting lever 41 to be rotated upward which consequently rotates form 38 upward, the combination of the two cam actions permitting form 38 to pass unobstructedly over the edge of tank 20a as shown in the third position of Fig. 1.

The combined raising and tilting of form 38 result in the toe of the form being the last part to leave the solution, thus providing adequate drainage of excess dipping solution and preventing formation of drops along the sole portion of the form.

The angle at which the form enters and leaves the dipping bath may be varied by rotation of shafts 68, which control the position at which inclined track members 61, 61 join upper cam track members 59, 59, thus making it possible to employ forms of any desired size and shape with dipping baths of any desired depth.

25 The cam action of raising and lowering form 38 by rotating lever 30 and the cam action of tilting form 38 to the desired angle by rotating lever 41, which cam actions are independent of each other, are repeated as carriage 17 is advanced over tank 20b which contains a coagulant for aqueous dispersions, tank 20c containing latex or other aqueous dispersions of rubbery material, and tank 20d containing water which washes uncoagulated latex or dispersion from form 38 and effects further "setting" of the coagulated deposit adhering to the surface thereof. After form 38 is withdrawn from dipping tank 20d it is removed by releasing the locking mechanism of clamping member 37 and another form is secured to clamping member 37.

30 Apparatus within the purview of my invention is particularly adapted to applying a coating or deposit of a rubbery material or the like to the surface of a base member of a glazed impervious material or the like or to a preformed member disposed over a form of the desired configuration.

35 40 The coating apparatus herein described produces hollow rubbery articles and articles coated with a rubbery material much more cheaply and efficiently than previously devised coating apparatus and there are realized great savings in labor and time.

45 50 The apparatus as disclosed above permits a base member to be immersed in a dipping solution to any desired depth, the depth to which the base member is immersed being readily altered by simple efficient adjustments to the apparatus.

55 55 My apparatus permits a base member to be drawn through a dipping bath in any desired angular position by merely making minor adjustments in the apparatus.

60 60 Forms or base members of numerous sizes and shapes may be coated by apparatus within the purview of this invention.

65 65 While the invention has been described with particular reference to one embodiment of the invention, it is clear that obvious variations and modifications are possible without departing from the spirit and scope of the invention as defined in the appended claims.

I claim:

1. Coating apparatus comprising a conveyor track, a carriage movable along said track and having means for holding an article to be coated, means for advancing said carriage along said track past a coating station, adjustable cam means disposed adjacent the path of said carriage at said station, said carriage having means actuated by said cam means as said carriage is advanced past said station for lowering and raising said article to and from a coating position, said cam means including adjustment means for altering the configuration of said cam means thereby varying the height to which said article is lowered as it is advanced past said station, and a second adjustable cam means disposed adjacent the path of said carriage at said station, said carriage having means actuated by said second cam means as said carriage is advanced past said station for tilting said article in a vertical plane to the angular position at which said article is coated and for returning said article to its origi-

of said carriage at said station, said carriage including means actuated by said second cam means as said carriage is advanced past said station for tilting said article-holding means in a vertical plane parallel to the path of travel of said carriage at said station to the angular position at which the article is coated and for returning said article-holding means to its original angular position after the coating operation, said second cam means including adjustment means for altering the shape of said second cam means thereby varying the angular position to which 10 said article-holding means is tilted for the coating operation as the carriage is advanced past said station.
